SAFETY ROADWAY CONSTRUCTION AND
ROTARY GUARD RAIL APPARATUS
THEREFOR

Harry J. Hick, Alliance, Ohio, assignor to The
Machined Steel Casting Company, Alliance,
Ohio, a corporation of Ohio

Application February 25, 1933, Serial No. 658,483

15 Claims. (Cl. 256—13.1)

My invention relates to safety roadway construction, including a roadway which may be the roadway of a land highway, vehicular bridge, and the like, and guard apparatus at one or more sides of the roadway, the roadway and the guard apparatus comprising a safety roadway construction in which the guard apparatus is so cooperatively arranged with respect to the roadway that vehicles, particularly passenger automobiles, busses, and motor trucks, which swerve or turn from the normal direction or path of movement in the traffic lane of the roadway will be prevented from leaving the roadway and will be deflected back into the traffic lane.

15 The usual types of guard rails, safety fences, and the like, which are provided along the sides of roadways, serve merely to obstruct a vehicle which has swerved or turned into a wrong direction or path of movement and is headed away 20 from the normal direction or path of movement in the traffic lane of the roadway and strikes the guard rail, safety fence, or the like.

An uncontrolled vehicle running out of the traffic lane of a usual roadway and running into 25 a usual safety guard rail, safety fence, or the like, is very frequently damaged; and when the speed of the vehicle is sufficiently high the safety guard rail, safety fence, or the like may be broken down or through by the vehicle, and 30 the vehicle may continue its uncontrolled course, and may fall into the ditch or ravine, or fall over the cliff, or fall off a bridge, near or on which the roadway may be located and be thus unsatisfactorily protected by the particular 35 guard rail, safety fence, or the like.

The objects of the present invention include the provision of improved safety roadway construction including a roadway and improved guard rail apparatus associated therewith, and 40 the operation of which is such that when a vehicle is swerved or turned from the normal path of movement in the traffic lane of the roadway, a wheel, and usually a front wheel of the vehicle will strike the improved guard rail apparatus and will be deflected thereby so as to direct the vehicle back into the normal path of movement in the traffic lane.

Further objects of the improvements include the provision of safety roadway construction including a roadway and guard rail apparatus, 50 so associated with each other, that the guard rail apparatus reacts with the wheel of a vehicle striking the same in such manner as to cause the impinged wheel of the vehicle to remain in its plane of movement with respect to the sur-

face of the roadway and not to rise from the same and jump or bounce over the guard rail apparatus.

Further objects of the improvements include the provision of guard rail apparatus particularly adapted for use in safety roadway construction, the guard rail apparatus having novel and simplified construction and arrangement, and being adapted for easy manufacture and erection.

The foregoing and other objects are attained by the improvements, constructions, apparatus, parts, combinations, and sub-combinations, which comprise the present invention, and the nature of which is set forth in the following general statement, and preferred embodiments of which, together with their mode of use, are set forth in the following description, and which are particularly and distinctly pointed out and set forth in the appended claims forming part hereof.

The nature of the present improved safety roadway construction and rotary guard rail apparatus therefor, may be stated in general terms as including a roadway which may be the roadway of a land highway, bridge, or the like, and rotary guard rail apparatus at one or more sides of the roadway, the rotary guard rail apparatus including a plurality of supporting means longitudinally spaced with respect to each other at 80 one side of the roadway, the supporting means preferably comprising post members, and a plurality of elongated roller or rotary guard rail members, each guard rail member being preferably longitudinally cylindric, and being rotatably mounted on opposite post members.

The rollers or rotary guard rail members extend longitudinally at the side of the roadway, and preferably a plurality of the rotary guard rail members extend longitudinally endwise 95 with respect to each other.

Each longitudinally extending rotary member is preferably rotatable independently of the other rotary members, and the rotary members are preferably arranged with their longitudinal axes co-extensive with each other or intersecting each other, and with adjacent ends preferably in rotary journal engagement with each other, and preferably in rotary thrust abutment against opposite sides of one of the post members.

The longitudinal axes of the elongated rotary members lie in a plane which preferably has a uniform elevation above the upper surface of the roadway, and the elevation of the plane of

- the longitudinal axes of the rotary members from the plane of the roadway upper surface is preferably less than the usual elevation of the axles of a usual motor vehicle from the same surface.
- Each post member is preferably provided at its bottom with a base which is preferably anchored in a longitudinally extending preferably concrete foundation block, the upper surface of which may be an extension of the upper roadway surface, and may slope, if desired, laterally with respect to the normal traffic lane portions of the roadway.
- The improved safety roadway construction and rotary guard rail apparatus therefor, furthermore preferably includes improvements in the construction and arrangement of certain parts as are hereinafter set forth and/or hereininafter set forth and claimed.
- Preferred embodiments of the improved safety roadway construction and rotary guard rail apparatus therefor, and of the parts thereof, are illustrated in the accompanying drawings forming part hereof, in which
- Figure 1 is a fragmentary isometric view of one form of the present improved safety roadway construction, including one preferred embodiment of the improved rotary guard rail apparatus therefor;
- Fig. 2, a fragmentary plan view of the improved guard rail apparatus of Fig. 1;
- Fig. 3, a side elevation thereof, with portions shown in longitudinal section;
- Fig. 4, an enlarged transverse sectional view of the improved safety roadway construction of Fig. 1, looking at the front end of the rotary guard rail apparatus thereof;
- Fig. 5, a fragmentary end view illustrating an embodiment of the improved rotary guard rail apparatus including parallel rotary members in a roadway construction having double traffic lanes;
- Fig. 6, an isometric view of another embodiment of the improved rotary guard rail apparatus;
- Fig. 7, a cross-sectional view thereof, substantially as on line 7—7, Fig. 6;
- Fig. 8, a fragmentary side elevation partially in section, illustrating another embodiment of the improved rotary guard rail apparatus, having a modified form of journal mounting for the rotary members; and
- Fig. 9, a fragmentary end view of still another embodiment of the improved rotary guard rail apparatus.
- Similar numerals refer to similar parts throughout the drawings.
- A preferred embodiment of the improved safety roadway construction is shown in Figs. 1 to 4 inclusive, and preferably includes a concrete base or foundation block 10 which is imbedded at one side of a roadway, which may be the roadway of a land highway, vehicular bridge, or the like, and which as illustrated is a paved roadway 11, the foundation block 10 extending longitudinally at one side thereof and being imbedded in the berm 12 at one side of the paved roadway 11.
- The upper surface of the base or foundation block 10 preferably slopes laterally upwardly from the upper surface of the paved roadway 11.
- The improved safety roadway construction furthermore preferably includes improved guard rail apparatus of which the foundation block
- 10 is a part, and which includes supporting means, preferably brackets or post members secured to the block 10, each post member being indicated generally by 13, and the post members being longitudinally spaced from each other with respect to the longitudinally extending block 10 and the longitudinally extending traffic lane or the paved roadway 11.
- Each post member 13 preferably includes a base plate 14 secured to the block 10 as by anchor bolts 15 imbedded in the concrete thereof. Preferably, an upright roller mounting member 16 projects upwardly from each base plate 14 at its longitudinally central portion, and is welded or otherwise secured to the base plate, or may be integral therewith.
- The upright roller mounting members 16 extend laterally of their respective base plates 14, and the post members 13 are preferably positioned on the block 10 so as to locate the members 16 at relatively short intervals, which, in this embodiment of the improved apparatus, are preferably approximately three feet.
- Each upright roller mounting member 16 is preferably provided adjacent its top end with a cylindric bearing aperture 17.
- An end roller guard rail member 18' is rotatably mounted in the upright members 16 of adjacent post members 13 at one end of the apparatus, and a roller or rotary guard rail member 18 is rotatably mounted between adjacent pairs of each of the other post members 13.
- Each of the rollers 18 and 18' is preferably cylindric and may be a length of pipe slightly less than three feet in length and preferably having an outer diameter of approximately four inches, so that it projects laterally somewhat beyond the upright members 16, although these dimensions may be varied considerably to suit various conditions.
- The longitudinal axes of the roller guard rail members are preferably located at an elevation which is less than 15 inches, or in other words has an upper limit of 15 inches, and is substantially 8½ inches above the upper surface of the base block 10, so that the guard rail members are below the axles and bumpers of usual motor vehicles.
- Each of the rollers 18 and 18' preferably has one end shrunk over a metal plug 19 fitting the inner diameter of the pipe, and each plug 19 has a journal stub 20 of reduced diameter, which is adapted to project beyond the end of the roller and through the bearing aperture 17 of an adjacent upright roller mounting member 16 for journaling therein.
- The other end of each roller 18 is preferably shrunk over an annular bearing member 21, and the bore 22 of each bearing member 21 is rotatably supported on the outer end portion of the journal stub 20 of the plug 19 of an adjacent roller. Preferably, the bore 22 of each bearing member and the diameter of each bearing aperture 17 is made slightly larger than the outer diameter of each journal stub 20 of the plugs 19, and the outer end portion of the journal stub 20 of each plug 19 is tapered as shown at 20', so that the roller guard members may be longitudinally angled slightly with respect to each other to conform to a curve in the highway, if desired.
- For facilitating assembly of the improved apparatus, the other end of the end roller 18' is preferably shrunk over an annular plug 23, 150

which is provided with an internally threaded bore 24. A journal stud 25 is screwed into the bore 24 and projects outwardly therefrom, and is journaled in the bearing aperture 17 of the end post member 13.

In assembling the improved guard rail apparatus the post members are located on the base block 10 in such a way that the longitudinal axes of the rollers 18 and 18' will be coextensive with each other, when the rollers are longitudinally aligned, and will intersect each other when the rollers are longitudinally angled with respect to each other, and the post members 13 are spaced longitudinally at proper intervals so as to position the ends of the roller members 18 and 18' in rotary abuttable relation with the sides of the adjacent upright member 16, when the apparatus is assembled.

Beginning at the rear end of the improved rotary guard rail apparatus, as viewed in Fig. 1, or at the left end thereof as viewed in Figs. 2 and 3, the journal stub 20 at one end of one of the rollers 18 is inserted through the bearing aperture 17 of the upright 16 at that end of the apparatus. Then the journal stub 20 of another roller 18 is inserted through the bearing aperture 17 of the next adjacent upright 16 and into the bore 22 of the bearing member 21 at the other end of the first roller 18.

This method of assembly is continued until the journal stub 20 of the roller 18 has been journaled in the adjacent upright 16 and in the next preceding roller 18, after which the journal stub 25 may be inserted through bearing aperture 17 of the end upright 16 and screwed into the annular plug 23.

The improved safety roadway construction is particularly adapted for use at a turn or curve in a land highway or as a safety roadway on a vehicular bridge, or the like, or wherever vehicles, and particularly motor vehicles are likely to swerve or turn from the normal path of movement in the traffic lane of the roadway of the land highway, bridge, or the like.

By locating the axes of the rollers at a predetermined distance above the upper surface of the foundation block 10, which is an extension of the upper surface of the paved roadway 11, such as eight and one-half inches, the bumpers or other outwardly projecting parts of a vehicle will pass entirely above the improved guard rail apparatus, when the vehicle swerves or turns into the apparatus, and the approaching wheel will strike one of the guard rail members in its lower front quadrant.

Accordingly, the shock of the impact between the vehicle and the apparatus is substantially always taken by the resilient rubber tires of the vehicle, thereby reducing damage to the vehicle or to the guard rail apparatus to a minimum.

Since the rollers are each rotatably mounted independently, when a wheel of a motor vehicle strikes one of the rollers as indicated in dot-dash lines in Fig. 2, the normal forward rotation of the wheel will rotate the roller downwardly in the direction of the arrow A and tend to prevent the wheel from rising above its plane of movement and from jumping or bouncing over the guard rail apparatus, at the same time deflecting the vehicle back into its normal path of movement.

In other words, the rotation of the roller by the impinging wheel tends to maintain the wheel upon the roadway, as contrasted with a stationary guard rail which would provide frictional

resistance to rotation of the wheel and tend to aid it in rising from the roadway.

The modified form shown in Fig. 5 comprises a double traffic lane safety roadway construction, and includes the base block 110 imbedded in the pavement 111. The post members indicated at 113 are secured to the base block by anchor bolts 115 and are adapted for journaling a double row of laterally adjacent preferably parallel elongated rollers 118 for presenting guard rail deflecting means to vehicles traveling in lanes at each side of the apparatus, and for preventing contact of the fenders, etc., of vehicles in side by side traffic lanes. In all other respects, the rotary guard rail apparatus shown in Fig. 5 is substantially the same as that shown in Figs. 1 to 4 inclusive.

The modified rotary guard rail apparatus shown in Figs. 6 and 7 is adapted to utilize relatively long lengths of pipe, and includes the base block 210 upon which the guard rail members are mounted.

The end brackets or post members 213 are substantially identical with the brackets 13 of the rotary guard rail apparatus shown in Figs. 1 to 4 inclusive, and the ends of the elongated roller 218 may be provided respectively with a plug having a reduced end portion and with a stud for journaling in the bearing apertures of said brackets.

Enlarged parabolically shaped ends 26 may be provided on the ends of the roller, the outer curved surfaces of which are adapted to deflect the wheel of a vehicle which strikes the roller longitudinally of its journal mountings in the post members 213.

Between the end post members 213 back-up post members 227 may be provided at regular intervals for reinforcing the roller 218 against impact. As best shown in Fig. 7, the upright roller mounting member 228 of each back-up member 227 is provided with a substantially circular notched portion 229 through which the roller 218 extends.

Balls or rollers 230 may be journaled at spaced intervals in the surface of the notch 229 to provide a roller bearing for the roller rail 218. Preferably, the notch 227 is made substantially less than a full circle so that the outer wall of the roller rail 218 projects laterally inwardly toward the highway beyond the upright roller mounting member 228, so as to receive the impact of a vehicle wheel striking the apparatus exactly at the location of an upright member.

The modified rotary guard rail apparatus shown in Fig. 8 includes the brackets or post members 313 mounted on the base block 310 and having the double ended journal stud 335 secured in the aperture 317 of the post member 313, with its ends projecting outwardly from opposite sides thereof.

The stud 335 is detachably secured in the post member preferably by means of a pin 336 which is screwed in the post member and passes through the stud.

In this form of the improved apparatus, the roller members 318 preferably have both of their ends shrunk over annular bearing members 321, which are journal mounted on the ends of the double ended journal stud 335.

The modified rotary guard rail apparatus shown in Fig. 9 is similar to the form shown in Figs. 1 to 4 inclusive, except that the rollers 418 are journal mounted in brackets or post

members 413 with the longitudinal axes of the rollers located a relatively short distance above the base block 410. This form is adapted for use in garages and the like, where the vehicles are driven at low speeds.

It will be observed that in each of the forms of the improvements above described, the brackets or post members constituting the longitudinally spaced supporting means may be

- 10 termed longitudinally spaced upright supporting means adapted for being mounted adjacent the traffic lane of a highway and the like, and each supporting means having a lower transverse plane adapted for location at the level of the upper surface of the highway and the like, and each form of the improvements furthermore includes one or more longitudinally extending rotary guard rail members journaled on the upright supporting means, the longitudinal axis
- 15 of rotation of each guard rail member being elevated above the transverse planes, and said transverse planes as illustrated being the lower surfaces of the base plates of the several brackets or post members 13, 113, 213, 313, and
- 20 413.

- I claim:
1. Guard rail apparatus for highways and the like, including longitudinally spaced upright supporting means adapted for being mounted adjacent the traffic lane of a highway and the like, a lower transverse plane of each supporting means being adapted for location at the level of the upper surface of the highway and the like, and a longitudinally extending rotary guard rail member journaled on the upright supporting means, the longitudinal axis of rotation of the guard rail member being located at an elevation above the highway level transverse planes which has an upper limit of fifteen inches.

2. Guard rail apparatus for highways and the like, including longitudinally spaced upright supporting means adapted for being mounted adjacent the traffic lane of a highway and the like, a lower transverse plane of each supporting means being adapted for location at the level of the upper surface of the highway and the like, and a longitudinally extending rotary guard rail member journaled on the upright supporting means, the longitudinal axis of rotation of the guard rail member being located at an elevation of substantially eight and one half inches above the transverse planes.

3. Guard rail apparatus for highways and the like, including longitudinally spaced upright supporting means adapted for being mounted adjacent the traffic lane of a highway and the like, a lower transverse plane of each supporting means being adapted for location at the level of the upper surface of the highway and the like, and a plurality of longitudinally extending rotary guard rail members journaled on the upright supporting means, the longitudinal axis of rotation of each rotary guard rail member being elevated above the transverse planes.

4. Guard rail apparatus for highways and the like, including longitudinally spaced upright supporting means adapted for being mounted adjacent the traffic lane of a highway and the like, a lower transverse plane of each supporting means being adapted for location at the level of the upper surface of the highway and the like, and a plurality of longitudinally extending externally cylindric rotary guard rail members journaled on the upright supporting means, the

longitudinal axis of rotation of each rotary guard rail member being elevated above the transverse planes.

5. Guard rail apparatus for highways and the like, including longitudinally spaced upright supporting means adapted for being mounted adjacent the traffic lane of a highway and the like, a lower transverse plane of each supporting means being adapted for location at the level of the upper surface of the highway and the like, and laterally adjacent longitudinally extending rotary guard rail members journaled on opposite sides of the upright supporting means, the longitudinal axes of rotation of the guard rail members being elevated above the transverse planes.

6. Guard rail apparatus for highways and the like, including three or more longitudinally spaced upright supporting means adapted for being mounted adjacent the traffic lane of a highway and the like, a lower transverse plane of each supporting means being adapted for location at the level of the upper surface of the highway and the like, and a longitudinally extending rotary guard rail member journaled on all of the upright supporting means, the longitudinal axis of rotation of the guard rail member being elevated above the transverse planes.

7. Guard rail apparatus for highways and the like, including longitudinally spaced upright supporting means adapted for being mounted adjacent the traffic lane of a highway and the like, a lower transverse plane of each supporting means being adapted for location at the level of the upper surface of the highway and the like, and a longitudinally extending rotary guard rail member journaled at its ends on the upright supporting means, the longitudinal axis of rotation of the guard rail member being elevated above the transverse planes, and back-up journaling means located between the supporting means and providing intermediate journal supports for the rotary guard rail member.

8. Guard rail apparatus for highways and the like, including longitudinally spaced upright supporting means adapted for being mounted adjacent the traffic lane of a highway and the like, a lower transverse plane of each supporting means being adapted for location at the level of the upper surface of the highway and the like, and a plurality of longitudinally extending rotary guard rail members journaled on the upright supporting means, the longitudinal axes of rotation of the rotary guard rail members being located in a common plane elevated above the transverse planes.

9. Safety roadway construction including a vehicular roadway and guard means adjacent the roadway, the guard means including longitudinally spaced upright supporting means and a longitudinally extending rotary guard rail member journaled on the upright supporting means, the guard rail member and its longitudinal axis of rotation being elevated above adjacent upper surface portions of the roadway.

10. Safety roadway construction including a vehicular roadway and guard means adjacent the roadway, the guard means including longitudinally spaced upright supporting means and a longitudinally extending rotary guard rail member journaled on the upright supporting means, the longitudinal axis of rotation of the guard rail member being located at an elevation above adjacent upper surface portions of the

roadway which has an upper limit of fifteen inches.	means, the guard rail member and its longitudinal axis of rotation being elevated above adjacent upper surface portions of the roadway, and the guard rail member projecting laterally beyond one side of the upright supporting means.	80
11. Safety roadway construction including a vehicular roadway and guard means adjacent to the roadway, the guard means including longitudinally spaced upright supporting means and a longitudinally extending rotary guard rail member journalled on the upright supporting means, the longitudinal axis of rotation of the guard rail member being located at an elevation above adjacent upper surface portions of the roadway which is substantially eight and one-half inches.	14. Safety roadway construction including a vehicular roadway and guard means adjacent to the roadway, the guard means including longitudinally spaced upright supporting means and a plurality of longitudinally extending rotary guard rail members journalled on the upright supporting means, the guard rail members and their longitudinal axes of rotation being elevated above adjacent upper surface portions of the roadway.	85
12. Safety roadway construction including a vehicular roadway and guard means adjacent to the roadway, the guard means including longitudinally spaced upright supporting means and a longitudinally extending externally cylindric rotary guard rail member journalled on the upright supporting means, the guard rail member and its longitudinal axis of rotation being elevated above adjacent upper surface portions of the roadway.	15. Safety roadway construction including a vehicular roadway and guard means adjacent to the roadway, the guard means including longitudinally spaced upright supporting means and a plurality of longitudinally extending rotary guard rail members journalled on the upright supporting means, the guard rail members and their longitudinal axes of rotation being elevated above adjacent upper surface portions of the roadway, and the rotary guard members having opposite ends adjacent one another and extending longitudinally endwise with respect to each other.	90
13. Safety roadway construction including a vehicular roadway and guard means adjacent to the roadway, the guard means including longitudinally spaced upright supporting means and a longitudinally extending rotary guard rail member journalled on the upright supporting	HARRY J. HICK.	100
